UNITED STATES PATENT OFFICE

ERNST KOBEL, OF ENNETBADEN, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND

RECTIFIER

Application filed February 28, 1930, Serial No. 432,034, and in Germany March 7, 1929.

This invention relates to improvements in electric power rectifying devices of the metallic vapour type in which an electric arc flows from an anode to a cathode through a body of material vapourized from the cathode by the arc, and more particularly to means decreasing the vapour density in the operating chamber or space between the anode and the cathode of such devices.

- 10 The arc in an electric power rectifying device is at a high temperature which vapourizes large quantities of the material from the cathode of the device which cathode is usually a liquid metal such as mercury. The large amount of vapour created produces a high vapour density in the operating space due to which some of the vapour may condense on the anode of the device thereby forming a so-called cathode spot which permits the flow of the electric arc from an anode to the cathode spot on the anode or on the rectifier container or tank when such spot is at a negative potential both with respect to the anodes and the cathode. Such action permits a flow of reverse current or back-fires through the rectifier with the attendant disturbance of the connected system and the danger of destruction of the rectifying structure itself.
- 20 The danger of the production of cathode spot may be largely eliminated if means are provided in the rectifier for decreasing the amount of material vapourized from the cathode thereby decreasing the vapour density in the operating chamber. Various cooling systems and cooling devices arranged interiorly on the rectifier have been proposed but none of the devices proposed completely attain the desired end, mainly the reduction of the amount of material vapourized from the cathode by the arc. In the operation of an electric current rectifying device of the character described, the electric arc moves or wanders over the surface of the cathode, and it has been found that, if such movement or wandering is restricted, the amount of vapour produced from the cathode is materially diminished, thereby diminishing the vapour density in the operating space of the rectifier and largely eliminating the danger

of the production of cathode spots and the danger of back-fires.

It is, therefore, among the objects of the present invention to provide an electric power rectifying device in which the amount and range of movement of the electric arc is largely restricted thereby preventing the production of an excessive amount of vapour within the device.

Another object of the present invention is to produce an electric current rectifying structure in which the area of cathode surface exposed to the action of the electric arc is controlled in dependence on the amount of current flowing through the structure.

Objects and advantages, other than those above set forth, will be apparent from the following description and the drawings, wherein:

Figure 1 is a central elevational view in section showing an embodiment of my invention, and

Fig. 2 is a diagrammatic view of circuits and apparatus embodying my invention.

Referring more particularly to the drawings by characters of reference, the reference numeral 1 indicates a portion of the bottom of a rectifier container or tank constructed in the usual manner and having an aperture therethrough, which aperture is surrounded exteriorly of the tank 1 by a substantially cylindrical wall 2 of insulating material closed by a plate 3. A water jacket 4 of any suitable construction is attached to the bottom of the cathode closure plate 3, for the purpose of providing a path for a cooling fluid supplied and discharged through the conduits 6 and 7 connected therewith.

A member 8 of insulating and refractory material, such as quartz, substantially in the shape of a truncated cone is arranged within the cathode well formed by the insulating wall 2 and the closure plate 3, in such manner that the open smaller base of the conical member extends into the mercury 9 forming the conductive portion of the cathode. The member 8 may also be formed of any electrical conducting material which does not amalgamate with the cathode material 3. The mercury normally extends into the cone-

shaped member 8 which thereby presents a cathode surface defined by the cone-shaped member 8, while all the remaining portions of the mercury are protected from the action of the arc. A conduit 11 leads from the bottom of the cathode closure plate 3 to a container 10 which is at least partially filled with mercury and contains a float or piston 113, retained in a predetermined position by a spring fastening 14. The float or piston 13 may, of course, rest freely on the surface of the mercury without a fastening of any kind. A coil 16 surrounds the container 12 and is connected to a portion of the rectifying circuit (not shown) for a purpose to be herein-after described.

Referring to the circuit arrangement shown in Fig. 2, it will be seen that by virtue of connection of coil 16 across the shunt 22, 20 a portion of the current flowing in the work circuit, including the secondary windings of transformer 17, conductor 18, translating device 19, conductor 20, shunt 21, conductor 22 and cathode closure plate 3, is diverted 25 through coil 16 and partially energizes the same.

As the amount of current increases and the intensity of the arc increases within the rectifier, the current flowing through the coil 30 16 increases so that the coil is more highly energized thereby, partially, at least, attracting the float or piston member 13. Increase of the current continues to increase the energization of the coil until the coil has attracted or drawn the float 13 downward sufficient- 35 ly to displace an amount of mercury proportionate to the amount of current flowing in the circuit. The amount of mercury cathode surface exposed is, therefore, directly proportional to the current flowing through the 40 circuit, which is further directly proportional to the intensity of the arc and to the amount of metallic vapour produced thereby.

It will be seen that the structure of the 45 present invention controls the amount of mercury cathode surface exposed in direct dependence on the amount of current flowing through this circuit. The electric arc flowing in the rectifying device is according- 50 ly prevented from moving or wandering over an extensive surface of mercury, thereby reducing the quantity of metallic vapour created and diminishing the vapour density within the operating space. It will be under- 55 stood that the coil 16 may be connected with any desired portion of the alternating current supply circuit or the direct current circuit desired, and that the area of cathode surface exposed to the action of the arc may 60 thus be controlled by the current values in any portion of the installation. The dynamic pressure of the positive mercury ions, as well as the reactive pressure of the mercury va- 65 pour may, therefore, be balanced or con-

trolled by variation of the mercury level in the container 12.

Although but one embodiment of the present invention has been illustrated, it will be understood that various changes may be 70 made therein without departing from the spirit of the invention or from the scope of the appended claims.

The invention claimed is:

1. In an electric current rectifying device 75 of the metallic vapour type, a metallic tank having an aperture through the bottom portion thereof, a well adapted to receive a liquid cathode material associated with the aperture in said tank, means associated with said well for defining the surface area of cathode material exposed to the interior of said tank, and means for controlling the area of exposed cathode material in dependence on the flow of current through the 80 device.

2. In an electric current rectifying device 85 of the metallic vapour type, a metallic tank having an aperture through the bottom portion thereof, a well adapted to receive a liquid cathode material associated with the aperture in said tank, means arranged interiorly of said well for defining the surface area of cathode material exposed, and means arranged exteriorly of said well for controlling the area of exposed cathode material in dependence on the flow of current through the 90 device.

3. In an electric current rectifying device 95 of the metallic vapour type, a metallic tank 100 having an aperture through the bottom portion thereof, a well adapted to receive a liquid cathode material associated with the aperture in said tank, means formed of refractory non-amalgamating material arranged interiorly of said well for defining the surface area of cathode material exposed to the interior of said tank, and means arranged exteriorly of said well and connected therewith for controlling the area of exposed cathode material in dependence on the flow of current through the rectifying device.

4. In an electric current rectifying device 115 of the metallic vapour type, a metallic tank having an aperture through the bottom portion thereof, a well adapted to receive a liquid cathode material associated with the aperture in said tank, a substantially conical member arranged within said well to extend 120 into the cathode material therein, to define the surface area thereof, and means associated and connected with said well for raising and lowering the cathode material level in response to the arc current in the rectifying 125 device.

5. In an electric current rectifying device 130 of the metallic vapour type, a metallic tank having an aperture through the bottom portion thereof, a well adapted to receive a liquid cathode material associated with the ap-

erture in said tank, a substantially conical member arranged within said well to extend into the cathode material therein to define the surface area thereof, an auxiliary container for cathode material arranged adjacent to and connected with said well, and means for controlling the amount of cathode material in said container in response to the flow of current through the rectifying device.

10 In testimony whereof I have hereunto subscribed my name this 13th day of February A. D. 1930.

ERNST KOBEL.
